MUFFLER

Elmer J. Dunham, Battle Creek, Mich., assignor to
 Clark Equipment Company, Buchanan, Mich., a
 corporation of Michigan

Application June 16, 1941, Serial No. 398,176

4 Claims. (Cl. 181—49)

This invention relates to mufflers, and more particularly is directed to a water muffler construction for use in connection with the exhaust from internal combustion engines and the like.

In connection with the use of internal combustion engines on trucks and tractors operating in locations where there may be a considerable quantity of dust on flowers or suspended in the atmosphere, or where there may be cotton lint or the like distributed around, such as in warehouses and other locations, it is desirable to preclude any possibility of fire caused by sparks being emitted from the muffler of the engine.

The present invention broadly contemplates the provision of a muffler for the exhaust of the engine which will contain water over which the hot exhaust gases must pass, whereby any sparks will be extinguished prior to the discharge of the exhaust gases to atmosphere.

While mufflers of this general type have heretofore been employed, it has been found that such mufflers are subject to criticism in that the water quickly evaporates therein and the operator may proceed with the operation of the vehicle without replenishment of supply, thus rendering the mufflers ineffective for the purpose for which it was provided. Also, the use of a muffler when the water has been evaporated produces a false sense of security and invites disaster in the way of fire and exposure.

The present design of muffler as disclosed herein has for its primary object to provide a construction in which the rate of evaporation of water is materially reduced, whereby the vehicle can be operated for from four to seven days without requiring replenishment of the water. In this connection, the present muffler is so designed that the hot exhaust gases passing thereinto pass through orifices of substantially equal area in moving into contact with the first volume of water. This eliminates any tendency to obstruct the flow of gases, eliminating also any back pressure in the exhaust manifold. The exhaust gases are led over a series of water compartments within the muffler, the velocity of the gases being such and the baffles being arranged in a manner so that the gases will contact the surface of the water in each compartment to eliminate any possibility of sparks being carried out through the outlet of the muffler.

In addition to this feature, I also provide a condensation or expansion chamber into which the gases are directed as they leave the last water compartment. In accordance with known

laws of physics, the expansion of the gases of this compartment reduces their temperature, and also provides for the dropping out of any foreign particles, which might be entrained therein due to the reduction in velocity produced by the expansion in volume. From this expansion chamber the gases, cooled and cleaned, are passed to atmosphere without any possibility of sparks being carried along therewith.

10 The muffler also has certain advantages in the arrangement of the baffle construction and the water compartments facilitating the filling of the water compartments and also facilitating drainage thereof when it is desired to clean and recondition the muffler.

15 The provision of a tortuous passageway through the muffler with the elimination of the possibility of back pressure insures that the gases will have thorough and intimate contact with the water before entering the expansion chamber, therefore quenching any sparks and at the same time not unduly restricting the flow of gases.

20 Other objects and advantages of the present invention will appear more fully from the following detailed description, which, taken in conjunction with the accompanying drawing, will disclose to those skilled in the art the particular construction and operation of a preferred form 25 of the present invention.

In the drawing:

Figure 1 is an elevational view of a muffler embodying the present invention;

30 Figure 2 is an end view of the muffler shown in Figure 1; and

Figure 3 is a top plan view, partly in section, of the muffler shown in Figure 1.

35 Considering now the construction in more detail, the muffler in general consists of a main body portion 5 of rectangular form having at one end thereof the entrance port 6 which is welded or otherwise secured to the top surface of the main body 5, as indicated at 7. A suitable connection 40 is made from the exhaust manifold to the entrance port 6, this port having the passageway 8 therethrough leading into the interior of the muffler. Disposed in a vertical position adjacent the port 6 and extending downwardly into the muffler is a transverse plate member 9 having the side flanges 10 secured to the side walls of the box. The area formed between the end wall 11 of the box and the transverse plate 9 is of a predetermined amount greater than the cross sectional area of the exhaust pipe whereby the

gas velocity is reduced as it enters the muffler system.

A suitable mounting bracket 12 is mounted to the end wall 11 of the box for supporting the muffler on the vehicle. The gases moving through the port 6 pass downwardly into the muffler 5 between the end wall 11 and the plate 9, and then move laterally beneath the lower end of the plate 9 into a chamber 13 formed between the opposite face of the plate 9 and a vertically extending baffle 14 supported on the bottom wall 15 of the muffler. The area of the passageway indicated at 16 between the bottom wall 15 of the muffler and the bottom of the plate 9 is substantially equal to the area between the plate 9 and the end wall 11, thereby providing no restriction to the flow of gas and insuring that the velocity will be maintained substantially constant as the gas flows around the lower end of the plate 9 and up into the chamber 13. The cross sectional area of the passageway between the plates 9 and 14 is substantially the same as the area between the plate 9 and the end wall 11 so that the gases may pass freely upwardly through this space toward the top of the muffler. As the gases reach the top of the muffler they encounter the inclined baffle 17 secured to the top wall 18 of the muffler and pass between the face of this baffle and the upper inclined edge 19 of the plate 14. The cross sectional area between the upper edge of the plate 14 and the baffle 17 is substantially equal to the areas previously referred to, and each of these areas is indicated by the letter X to show that they are substantially equal. Passing through the last-named space, the gases enter into the first water compartment, indicated at A, in which the water level is maintained substantially to the line L. The water in this chamber is confined between the plate 14 and a longitudinally spaced plate 20 supported on the side walls of the muffler by means of flanges 22. The upper end of the plate 20 is bent rearwardly, as indicated at 23, to form a trap so that the gases must contact the surface of the water in the compartment A prior to leaving this compartment between the baffle 17 and the flange 23.

It will be noted that the plate 20 is spaced a slight distance above the bottom wall 15 of the muffler, as indicated at 24, whereby the level in all of the water compartments is maintained substantially equal. After passing through the water compartment A, the hot gases again move upwardly toward the top wall 18 of the muffler, and are directed downwardly by the baffle 25 into the second water compartment 13. This compartment is of substantially the same volume as the compartment A, and is defined between the transverse plates 20 and 26, the plates being secured to the side walls of the muffler by the flanges 27. The plate 26 is also provided with a normally directed top flange portion 28 similar to the flange 23 to insure intimate contact of the gases with the surface of the water in the compartment B.

From this compartment, the gases are again directed upwardly toward the top 18 of the muffler, encountering the baffle 29 which is similar to the baffles 17 and 25. From this point the gases are directed downwardly into the water compartment C, defined by the flange 26 and the opposite end wall 30 of the muffler. The compartment C is fed with water through the inlet opening or port 32, and a suitable drain opening 33 is provided adjacent the bottom of the muffler for draining out the water in the compartments A, B and C in order to clean the muffler.

Over the top of the water in the compartment C there is provided a baffle 34 which has depending side flanges 35 secured to the side walls of the muffler, thereby producing intimate contact of the gases with the water in the compartment C after which these gases move upwardly through the opening 36 in the top wall 18 and thence to the expansion chamber indicated generally at 37. Disposed over the top of the opening 36 and inclined in an upwardly direction is the baffle plate 38 secured as at 39 to the end wall 30 of the muffler. This baffle protects discharge of the gases directly through the opening 36 into the exhaust outlet 40 at the top of the expansion chamber 37, insuring that the gases will expand within the chamber 37 to reduce the temperature thereof and also to insure that any particles entrained in the gases will be impacted against the under surfaces of the baffle 36 and dropped back into the muffler. From the outlet 40 the gases are discharged to atmosphere, any sparks or the like having been previously extinguished and the gases having been reduced in temperature and velocity by passage through the muffler. A bracket 42 is provided at this end of the muffler for supporting the same.

It will be noted that the opening between the flange 23 and the baffle 25 and between the flange 28 and baffle 29 are larger than the openings X, insuring that there is no restriction of the gases as they pass from the initial compartment A to the compartments B and C. This provides for reducing the velocity of the gases and allowing some expansion thereof which also effects cooling, although the expansion is not as pronounced as that which occurs in the chamber 37.

I have found that with a muffler constructed in accordance with the present teachings, the rate of evaporation of the water in compartments A, B and C is materially reduced due to the control of the velocity and pressure of the gases within the muffler. At the same time, there is no tendency to create a back pressure in the exhaust manifold. Further, such a construction insures intimate contact with at least three bodies of water, thereby assuring that any sparks carried in the gases will be completely extinguished prior to discharge of the gases to atmosphere. It will also be noted that the expansion chamber 37 provides for a reduction in both the velocity and the temperature of the gas to be sure that when the gas is discharged to atmosphere it will be cool. In tests, it is possible to hold the hand at outlet 40, since the temperature of the gases has been so reduced through the muffler.

I am aware that various changes may be made in certain details of the present construction, and I therefore do not intend to be limited except as defined by the scope and spirit of the appended claims.

I claim:

1. A water muffler comprising a rectangular body portion of appreciable depth, an exhaust gas inlet port extending through the top of said muffler at one end thereof, baffle means for causing gases entering through said port to flow to the bottom of said muffler and then upwardly to the top thereof without materially changing the cross-sectional area of said path, a series of longitudinally spaced water compartments extending to the opposite end of said muffler, deflector means for directing said gases as they reach the top of said muffler successively into contact with the surface of the water in each compartment,

an expansion chamber disposed on the top of said muffler at said opposite end thereof, means defining a port leading from said muffler into said chamber, an exhaust port in the top of said chamber, and a baffle plate preventing direct flow of gases through said last-named ports.

2. In combination, in a water muffler having a rectangular box-like body portion provided with an inlet port at one end and an exhaust port at the opposite end, a first transverse vertical baffle terminating short of the bottom of the muffler adjacent said inlet port for causing gases entering therethrough to pass downward at said one end and thence under said baffle without materially changing the cross-sectional area of said path, a second transverse vertical baffle terminating short of the top of said muffler and spaced longitudinally of said first baffle a distance equal to the distance between said first baffle and the end wall of said muffler, an exhaust port in said muffler at the top of the opposite end thereof, a longitudinal series of water compartments between said second baffle and said opposite end of said muffler, and transversely arranged deflector members secured to the top wall of the muffler for directing said gases successively into contact with the surface of the water in said compartments.

3. The combination of claim 2 further char-

acterized in the provision of an expansion chamber between the last water compartment and said exhaust port.

4. In combination, in a water muffler having a rectangular box-like body portion, a first vertically extending transverse baffle spaced a predetermined distance from the end wall of said muffler and terminating at a point spaced the same distance from the bottom of the muffler, 5 a second vertically extending transverse baffle spaced the same distance from said first baffle and terminating short of the top wall of the muffler, an inlet port opening into the top of said muffler between said end wall and first baffle 10 for introducing exhaust gases thereto, a series of water compartments extending from said second baffle to the opposite end wall of said muffler, deflector means secured to the underside of the top wall adjacent the anterior side of each compartment for directing said gases successively 15 onto the surface of the water in each compartment, and an expansion chamber above the last compartment for reducing the pressure of said gases prior to discharge, said baffles insuring at least three changes of direction of gas flow prior to entrance into said first compartment without any change in the cross-sectional area of 20 the gas path.
